UNITED STATES PATENT OFFICE.

CHARLES M. EBERLING, OF CLEVELAND, OHIO, ASSIGNEE TO THE EBERLING MACHINES SALES COMPANY, OF CLEVELAND, OHIO, A CORPORATION OF OHIO.

CONCRETE-MIXING APPARATUS.

Application filed December 20, 1920. Serial No. 431,908.

To all whom it may concern:

Be it known that I, CHARLES M. EBERLING, a citizen of the United States, residing at Cleveland, in the county of Cuyahoga and State of Ohio, have invented a certain new and useful Improvement in Concrete-Mixing Apparatus, of which the following is a full, clear, and exact description, reference being had to the accompanying drawings.

This invention relates to a machine for mixing dry materials and especially for intimately mixing cement with an aggregate and water so as to produce a uniform mixture of the desired consistency. The objects of the invention are the provision of a machine of the continuous operation type in which an absolutely uniform and regular mixture of the materials shall at all times be produced; wherein the proportions of the dry ingredients such as cement and aggregates can be readily adjusted and after adjustment will remain constant indefinitely; one wherein the proportions of the material will to some extent vary automatically with the size of the aggregates or the lumpiness of the cement; one wherein the mixing trough can readily be adjusted to prevent or compensate for wear and replacement when necessary; while further objects and advantages of the invention will become apparent as the description proceeds.

In the drawings accompanying and forming a part of this application, I have shown certain physical forms in which my inventive idea can be embodied although it will be understood that these drawings are intended to be merely illustrative of principles rather than exhaustive of constructions; Fig. 1 represents a plan view of a complete concrete mixer of my invention; Figs. 2 and 3 represent vertical longitudinal sectional views of the same corresponding to the lines 2-2 and 3-3 of Figs. 4 and 5. Fig. 4 is a front elevation of the machine; and Fig. 5 is a transverse sectional view taken on the broken line 5-5 of Figs. 1 and 3.

Describing the parts by reference characters my improved machine comprises a trough 1 in which the ingredients are mixed, and two hoppers 2, 3, in which the cement and aggregate, respectively are introduced and from which they are fed to the trough in adjusted proportions; 4-4 represent par-

allel side members of a horizontal rectangular frame, connected by suitable bolsters 5-5 which carry the bearings 6-6 and also supported by the legs 7-7. Journaled in the bearings is a pug shaft 8 to which are attached the inclined blades 9-9 spaced at intervals therealong. The trough 1 is made of sheet metal with vertical sides 10-10 and a semi-cylindrical bottom 11 past which the ends of the blades swing closely in order to prevent the aggregate from entering therebetween and cutting channels in the metal. The upper edges of the trough walls are provided with suitable outturned ears 12-12 attached by means of vertical bolts 13-13 to a suitable part of the frame such as the cross bars 14. By this construction the trough can be adjusted vertically to bring it into the proper relation with the knives, or can be dropped completely from its support for repair or replacement without dismantling any other part of the machine. This trough is shorter than the shaft 8 and is located entirely between the bearings 6-6, its head-end terminating in a wall 15 which is apertured for the shaft, and its opposite end being open as shown at 16 for the discharge of the mixed material. In this way the main bearings are preserved out of contact with the abrasive materials, which is further accomplished if desired by interposing a shield 17 between the discharge end of the trough and the corresponding shaft-bearing.

Carried by the forward end of the frame 4 are a pair of longitudinally spaced brackets 20, 21 in which are journaled the parallel, horizontal feed shafts 22, 23 which are located one above each side of the machine, parallel to the shaft 8 and traversing the hoppers 2 and 3 respectively. Rigidly secured to each of these shafts is a circular member 24 here shown as having a pair of outturned peripheral flanges 25-25 formed with alighted apertures parallel to its axis, and in said apertures are slidably mounted the fingers 26-26. The rearward ends of these fingers 26 are turned inwardly as shown at 27 and received in the peripheral groove of an adjusting disk 28 slidably mounted upon the corresponding shaft; such adjustment being effected by means of a hand wheel 29, a drag screw 30, and a pivoted lever 31, the latter being connected to the disk by means of the slip ring 110

32. By this construction the forward ends of the fingers can be caused to project a greater or less distance upon the rearward side of their respective carriers.

33. Projecting from the forward face of the hoppers 2 and 3, are the spouts 35 and 36, respectively which extend into the space defined by the rotating ends of the fingers 26 and are terminated by the upright plates 37 through which the respective shafts pass. Beneath the discharge end of these spouts are located the shelves 38, 39, made in the form of cylindrical segments with their concave sides uppermost, across which the ends of said fingers sweep closely, the end plates 37 the sides of the spouts terminating sufficiently above these shelves to define slots 40 through which these fingers pass. Leakage of material through these slots is prevented by the fact that the plates 37—37 lie so close to the member 34 that the adjacent flange 25 forms a moving closure, while the ends of the shelves are extended laterally a sufficient distance as shown at 41—41 to prevent the overflow of the material.

34. Carried by the forward ends of the shafts 22, 23 are the intermeshing spur gears 44—44 by means of which the shafts are turned in opposite directions as shown by the arrows in Figs. 4 and 5; and suitable means are also provided for the driving of the shaft 8 and the connection of the other shafts thereto in driven relation. In the present embodiment I have shown the shaft 8 as provided with fast and loose pulleys 45, and also a sprocket 46 from which a chain 47 leads to a larger sprocket 48 whose hub 49 is sleeved loosely on the shaft 22. The exterior of this hub is formed with a cylindrical portion 50 on which is slidably and rotatably mounted the hub 51 of a smaller sprocket 52, which in turn is connected by a chain 53 with a large sprocket 54 rigidly connected to the shaft 23. Journaled upon the end of the shaft 23 is a collar 56 to which is pivoted the clutch lever 57 whose opposite end engages the split ring 58 carried by the hub 51; while the hubs 49 and 51 are formed with interfitting clutch teeth as shown in Fig. 1 so that by the operation of this lever the operation of the shafts 22 and 23 can be controlled without stopping the shaft 8.

35. Inside the hoppers the shafts are provided with stirring arms 60. Also adjacent to the point at which the fingers 26 leave the shelves 38 and 39, the adjacent walls of the hoppers are provided with pivoted doors 61—61 hung on horizontal spring hinges 62—62 so as normally to remain closed, but adapted to be opened momentarily by engagement with a stone or hard lump in the material. Also I locate a suitable water supply head such as the rose 65 above the trough 1 slightly to the rear of the shelves.

36. These hinges are preferably attached to plates 63—63 which are vertically adjustable through the agency of slots 64 whereby the width of the discharge openings can be varied to accommodate coarse material or different conditions of moisture.

37. The operation of my improved machine is as follows: The hoppers 2 and 3 being filled, the one with cement and the other with a suitable aggregate, which may be of crushed stone, gravel, sand, or other suitable substance, regardless of size (within the capacity of the machine) the three shafts are set into rotation, whereupon the action of the fingers 26 sweeping across the shelves 38 and 39 is to carry measured amounts of the two materials simultaneously therefrom and shower them into the trough. The comparative proportions of the respective materials depends upon the relative speed of the shafts 22 and 23 and upon the relative amounts by which the fingers 26 project across the shelves, the latter adjustment being capable of variation even while the machine is in operation by merely turning the hand wheels 29—29. The width of the slots is also a factor to be taken into consideration. In the present embodiment I have shown the spur gears 44—44 as being of equal size, thereby working the shafts at the same speed, but it is sometimes desirable to rotate the one which feeds aggregate more rapidly than the other. In any case, it will be seen that the two materials, cement and aggregate, are showered together continuously in the dry state so as to become closely mixed in the dry state even in the act of falling into the trough. Being almost immediately shoved by the knives beneath the water spray, they become worked into a uniform consistent mass before any segregation can occur, and delivered in a uniform stream of any desired degree of wetness. The length of the trough and slope of the knives are so chosen as to afford a sufficient degree of mixture before discharge. In order to stop the machine it is customary first to throw off the clutch lever 57 so as to stop the addition of the dry materials, and also shut off the water supply, but leaving the pug shaft in operation until the trough has been freed from concrete mixture.

38. In case a stone becomes caught by the aggregate-feeding fingers, the corresponding spring door yields, permitting its passage without injury to the machine; and although its effect is also to permit a momentary increase in the proportion of aggregate, this is not a serious matter, partly because in fine work care is taken to avoid the presence of stones, and in rough work a little variation in aggregate, particularly when it is of a coarse texture, is no detriment. Likewise if the cement be lumpy the spring doors yield to permit its passage, and the fact that

such yielding serves to permit the passage of an undue quantity of cement at such times is no real disadvantage inasmuch as an added quantity of cement must in any case 5 be used when it is of a lumpy nature. The doors close very quickly after they have opened, and with reasonably uniform materials experience shows that the proportions can be adjusted and maintained with my invention 10 proved mixer with a high degree of satisfaction and most important, that the proportion of liquid to solid can be maintained with great accuracy which is of especial value in connection with compressing machinery 15 in which the amount of pressure must be governed to some extent by the moisture of the mixture. It will be understood that my improved mixer is equally useful in the production of wet and fluid mixtures, 20 can be made in any desired size or capacity. It can also be used for mixing other materials than those described, especially certain parts of the mechanism, since it is clear that other parts can be substituted or omitted, 25 and generally that many changes in detail and construction can be made within the scope of my invention.

Having thus described my invention what I claim is:

30 1. In a concrete mixer, the combination of a trough having pugging means therein, of a pair of fixed shelves overhanging said trough opposite to each other, rotatable pushing devices adapted and arranged to sweep across the top of said shelves, means for maintaining a uniform supply of cement and aggregate on the respective shelves, means for rotating the pushing devices whereby the same may sweep simultaneously 35 across said shelves toward each other, and means for varying the effective length of said pushing devices.

2. In a concrete mixer, the combination of a trough having pugging means therein, of a pair of shelves overhanging the same opposite to each other, hoppers for cement and aggregate supported one above each shelf and each having a discharge spout which terminates slightly above and inside 40 the edges of the corresponding shelf, a series of pushing devices movable across each shelf past the end of the spout, and means for rotating said pushing devices continuously in a direction to shower into said trough some of the dry material thereon.

55 3. In a concrete mixer, the combination of a trough having pugging means therein, of a pair of shelves overhanging the same, hoppers for cement and aggregate supported one above each shelf and each having a discharge spout which approaches the corresponding shelf sufficiently far from its discharge side to prevent accidental overrunning, a pushing device supported for 60 movement across the face of each shelf,

means for moving said devices simultaneously toward the discharge sides of their respective shelves, and means for varying the effective lengths of said devices so as to adjust the respective amounts of cement and aggregate which they shower into the trough. 70

4. In a concrete mixer, the combination of a trough having pugging means therein, of a pair of shelves overhanging the same, a wall at the discharging side of each shelf and spaced thereabove to define a discharge slot, means for maintaining a supply of dry material on each shelf, fingers adapted to sweep across said shelves and through said slots so as to shower into said trough the material on said shelves, and means for varying the effective length of said fingers. 75

5. In a concrete mixer, the combination of a trough having pugging means therein, of a pair of shelves overhanging the same, a wall at the discharging side of each shelf and spaced there above to define a discharge slot, means for maintaining a supply of dry material on each shelf, pivoted fingers adapted to sweep across said shelves and through said slots, means for actuating simultaneously the fingers for the respective shelves, and means for adjusting said fingers so as to vary the speed of the dry material through their respective slots. 80

6. In a concrete mixer, in combination an upwardly concave shelf constituting a cylindrical segment, a shaft concentric therewith, a circular member carried by said shaft, and constituting a closure for one end of said shelf, a plurality of spaced fingers projecting from said member and adapted to sweep across the face of said shelf as the member is revolved, a hopper for dry material having a spout projecting into the space defined by said fingers and discharging onto said shelf, means for rotating said member, and a receptacle for the material which said fingers remove from said shelf. 100

7. In a concrete mixer, in combination a shelf concave on its upper side constituting a cylindrical segment, a shaft concentric therewith, a circular member carried by said shaft, and constituting a closure for one end of said shelf, a plurality of spaced fingers projecting from said member and adapted to sweep across the face of said shelf as the member is revolved, means for maintaining on said shelf a supply of dry material, means for rotating said member, and means for varying the length of said fingers. 115

8. In a mixing apparatus, in combination, an open topped trough having pugging means therein, a pair of horizontal shafts above and at opposite sides of said trough, a plurality of spaced fingers arranged about each of said shafts and parallel therewith and spaced therefrom, shelves over which said fingers sweep as said shafts are re- 120 125 130

volved, the discharge sides of said shelves overhanging said trough, means for rotating said shafts in opposite directions, and means for delivering dry materials to said shelves and constituting covers for said shelves having depending sides spaced from the sides of said shelves.

9. In a mixing apparatus, in combination a pair of hoppers having spouts, a pair of 10 shelves onto which said spouts discharge, said spouts extending above said shelves and constituting a cover therefor, a shaft adjacent to each shelf, fingers carried by said shafts and adapted to sweep over said 15 shelves as said shafts are revolved, a common receptacle located beneath the discharge sides of said shelves, and means for rotating said shafts simultaneously, said spouts being spaced from said shelves sufficiently 20 to allow the passage of said fingers.

10. In a device of the character described, in combination, a shelf made in the form of a cylindrical segment and supported with its axis horizontal and its concave surface upward, a horizontal shaft concentric with said segment, a circular member carried by said shaft, a plurality of spaced fingers carried by said member parallel to the shaft and adapted to sweep over said surface as said 25 shaft is revolved, and a discharge spout projecting lengthwise into the surface of revolution defined by said fingers.

11. In a device of the character described, in combination, a shelf made in the form of a cylindrical segment and supported with its axis horizontal and its concave surface upward, a horizontal shaft concentric with said segment, circular members carried by said shaft, and having spaced apertures 30 therein aligned in parallelism to said shaft, fingers slidably mounted in said apertures and adapted to sweep over said surface as the shaft is revolved, a member to which all 35 said fingers are attached, and means for adjusting said member along the shaft.

12. In a device of the character described, in combination, a shaft, a circular member thereon and having a plurality of pairs of aligned apertures therein equidistantly 40 spaced from said shaft, rods slidably mounted in said apertures and projecting beyond said member on one side, a second member carried by said shaft at the opposite side of said first member and connected to said 45 rods, and means for adjusting said second member longitudinally of said shaft.

13. In a concrete mixer, a container having pugging means therein, a pair of separate containers for cement and aggregate respectively, shelves on which said last 50 containers discharge, a succession of revolubly mounted fingers located outside of each con-

tainer and arranged and adapted to sweep across the respective shelves, and means for revolving said fingers continuously in a direction to sweep measured amounts of the 65 respective materials into said first container.

14. In a concrete mixer, the combination with a trough having pugging means therein, of a pair of shelves located at a higher 70 level than said trough and overhanging the same at opposite points, a succession of revolubly mounted fingers arranged and adapted to sweep over said shelves, means for revolving said fingers continuously in a direction to sweep from said shelves into said 75 trough, and a pair of hoppers for cement and aggregate respectively having spouts projecting inside the line of travel of said fingers and terminating at such distance 80 above said shelves as to permit said fingers to pass beneath the same.

15. In a concrete mixer, the combination of a trough having pugging means therein, of a pair of shelves overhanging said trough 85 on opposite sides, a succession of pushing devices movable across the top of each shelf transversely of the trough, means for maintaining a uniform supply of cement and aggregate on the respective shelves, and means for moving the pushing devices simultaneously 90 toward each other by a constant movement in one direction, so as to shower the cement and aggregate simultaneously into said trough.

16. In a mixing apparatus, a receptacle having pugging means therein, a pair of shafts located at opposite sides thereof, a plurality of spaced horizontal fingers carried by said shafts, a pair of shelves formed 100 as surfaces of revolution over which said fingers sweep as said shafts are revolved, the discharge sides of said shelves overhanging said receptacle, hoppers for delivering dry material to said shelves, and means for rotating said shafts so as to cause said fingers to sweep over said shelves beneath said hoppers so as to shower such material into said 105 receptacle.

17. In a concrete mixer, in combination with a trough having pugging means therein, a plurality of shelves located at a higher 110 level than said trough and overhanging the same, means for delivering dry concrete making materials to the respective shelves, means traveling across the tops of said shelves adapted to sweep such concrete making materials into said trough and means for controlling the relative rate of ejection 115 of such materials from the different shelves.

In testimony whereof, I hereunto affix my signature.

CHARLES M. EBERLING.
